United States Patent Office

Des. 197,119
Patented Dec. 17, 1963

197,119

WINDOW

Andrew Rocco, 512 Nevada St., El Segundo, Calif., and
Glen S. Schweitzer, 2211 Grant Ave., Redondo Beach,
Calif.

Filed Nov. 5, 1962, Ser. No. 72,382

Term of patent 14 years

(Cl. D13—1)

FIGURE 1 is a front elevational view of a window showing our new design;

FIGURE 2 is a rear elevational view;

FIGURE 3 is a transverse section taken substantially along the plane of line 3—3 in FIGURE 1; and

FIGURE 4 is a top plan view.

We claim:

The ornamental design for a window, substantially as shown.
